(57) **CLAIM**

The ornamental design for an outdoor canopy, as shown and described.

DESCRIPTION

FIG. 1 is a perspective view of an outdoor canopy showing our new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged partial view a portion of the corner post taken from FIG. 2; and,

FIG. 10 is an enlarged partial view of a portion of the window taken from FIG. 2.

The dash-dash broken lines in the drawings depict portions of the outdoor canopy that form no part of the claimed design. The dot-dash broken lines represent boundaries of the enlarged portions and form no part of the claimed design.

1 Claim, 10 Drawing Sheets
